UNITED STATES PATENT OFFICE.

WILLIAM F. LAUTENSCHLAGER, OF CINCINNATI, OHIO, ASSIGNOR TO LORENZ MUTHER,
OF NEWTON, MASSACHUSETTS.

PRESSING DEVICE.

1,259,880.

Specification of Letters Patent. Patented Mar. 19, 1918.

Application filed August 20, 1915. Serial No. 46,520.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Pressing Devices, of which the following is a specification.

My invention relates to a pressing device applicable for pressing flexible material in machines such as folding machines for folding the edges of shoe uppers or other flexible material used for instance in gloves, pocket-books, and other articles; in beading machines for pressing or beading for instance the beads at the sides of the seam of a shoe upper; in shoe-upper blocking machines, and other machines employing a presser acting on the flexible material.

I have exemplified my invention as employed in a folding machine such as shown, described and claimed in my application for Letters Patent of the United States on improvements in folding machines, Serial No. 634,485, filed June 21, 1911. I have in the drawings exemplified the pressing device as employed for pressing the margin of flexible material being folded, such as a shoe upper, and have indicated the feeding, snipping, and folding means of such a machine. These means as well as the pressing device may be operated in manner similar to that shown, described and claimed in my aforesaid application.

My invention will be further readily understood from the following description and claims, and from the drawings, in which latter:

Figure 1 is an end elevation of so much of the folding machine as is necessary to illustrate my invention.

Fig. 2 is a side elevation of the same.

Fig. 3 is a plan view of the same.

Fig. 4 is a rear end elevation of the operating means for the presser.

Fig. 5 is a central cross-section on the line 5-5 of Fig. 3, shown in connection with a piece of flexible material, with the fold portion of the margin of the material about to be laid upon the body portion of the margin, and in the relation in which the presser is about to exert pressing action upon the fold being laid.

Fig. 6 is a similar view, showing the

presser in pressing relation, with the body of the presser shifted with relation to its pivot for exerting its pressing function.

Fig. 7 is a vertical axial section on the line 7-7 of Fig. 2; and,

Fig. 8 is a diagrammatic representation showing the changes in relation of the parts during operation in the present exemplification.

11 represents a material-support, which may be horizontal as shown, or placed at any desired angle with relation to the horizontal, or in vertical position, as may be desired.

12 represents a feeding-foot, operated in manner heretofore mentioned, designed to coöperate with a feeding roller 13, to impart step-by-step or progressive feeding movements to the piece of flexible material, exemplified at 14. A snipping knife 15 may if desired be employed and is arranged to co-act with a snipping block 16, and is designed to snip or cut the fold-portion of the margin to be folded, crosswise of the fold, when desired, during the feeding movements.

A folding block 19 has a plow-shaped folding face and is arranged to partially turn the fold-portion 21 of the margin of the material, for instance along a fold 22, the position of which is determined in suitable manner, and is instanced as determined by the folding block in connection with the fold-presser.

25 represents the presser instanced as a fold-presser, and is arranged to normally oscillate about a pivot 26. This pivotal axis of the pivot is shown in substantially the plane of the material-supporting face or anvil 27 of the material-support. The pressing-face 28 of the presser is arranged to co-act with the material-support 11, in close proximity to the pivot position of the presser so as to reduce the throw of the pressing portion of the presser as much as possible.

When the presser has been swung toward the material-support in such relation as to begin the pressing function upon the material, the pressing face of the presser is preferably distanced from the material-supporting face of the material-support at its point of closest approach to the material, a distance equal to the thickness of the folded margin of the material employed, this dis-

tance being adjustable by the adjustment of the body of the presser hereinafter described.

The pivot of the presser is exemplified as 5 a shaft, which may be a stationary shaft, fixed in bearings 30 of the main frame 31 of the machine. A bushing 32 is received about the shaft, the bushing rocking about the shaft with the body of the presser. This 10 bushing is in a slot 33 in the presser, the presser being movable lengthwise of this slot and crosswise of the bushing and pivot shaft 26.

There is a socket 34 in the presser, in 15 which a spring 35 is located. 36 is an adjusting screw adjustable in the threaded end 37 of the socket and is arranged to adjust the tension of the spring 35. This spring adjusts the pressure applied by the 20 presser.

For adjusting the normal position of the body of the presser and the distance of its pressing face from the material-supporting face of the material-support when in pressing relation, I provide a set-screw 38 in a threaded hole 39 of the presser, arranged to contact the bushing for adjusting the distance between the upper end of the slot and the bushing and positioning the pressing 30 face of the presser with relation to the supporting face of the material or anvil, for accommodating different thicknesses of material. The set-screw is locked in place by means of a lock-screw 40, screwed in the 35 threaded hole 39 upon the set-screw 38.

For operating the presser I have instanced a shaft 44, which has a crank-pin 45 thereon, which is articulated with the tail 46 of the presser by means of links 47, 48 and 49. 40 The link 47 has a bearing 52 about the crank-pin 45. A pivot-pin 53 connects the links 47, 48, by being located in bearings 54 of the link 47 and a bearing 55 of the link 48. The links 48 and 49 are connected by 45 a pivot-pin 57 located in bearings 58 of the link 48 and in a bearing 59 of the link 49. The link 49 has a bearing 60 arranged within fork-like bearings 61 in the tail 46, an articulating pin 62 being located in said 50 bearings.

If desired, the spring 35 may extend into a socket 64 in the adjusting screw 36, and be held at its lower end against an annular shoulder 65 therein.

55 I have in Fig. 8 diagrammatically illustrated the preferred relation of the presser to the material-support, when the pressing face 28 of the presser has been moved by the operating means toward the material-supporting face, and in the absence of material between the pressing face and the material-supporting face. In such relation the presser-face 28 is preferably distanced, as by the space 68, from the material-supporting face 27 of the material-support 11, but

parallel therewith. This space represents for instance the thickness of the pressed folded portion of the material.

The pivotal axis 26 of the presser is in the plane of the material-supporting surface, represented by the dotted line 69, the articulating axis 62 of the operating means being preferably also in this plane, when at its uppermost limit of movement.

In operation, the fold-portion of the margin being folded is partially folded by the folding-block 19. The partially folded fold-portion is laid toward the body-portion of the margin along the fold 22, by a rocking movement of the presser about its pivotal axis 26, with the body of the presser in normal relation with the pivotal axis, as illustrated in Fig. 5, the articulating axis 62 being now below the plane of the material support.

85 A further movement of the axis of articulation 62, instanced as an upward movement, will cause pressure to be exerted upon the fold being pressed, causing yield of the body of the presser at its pivotal axis 26, (see Fig. 90 6), for pressing the fold-portion upon the body of the margin with a movement of the fold-pressing face of the presser direct toward said body, whereby lateral shifting of the fold-portion and fold is prevented, and 95 the fold caused to be laid in a true line.

In order to insure such movement I arrange the slot 33 on an arc, illustrated by the dotted line 70 in Fig. 8, described from the point 71 in the pressing-face 28 as a 100 center, this center-point representing the point of contact of the pressing face with the fold 22. This has the further advantage in that it insures pressure upon said fold, and enables a thin fold-edge, much desired in 105 shoe-making practice, to be obtained.

In the pressing movement, the presser practically swings upon the fold-portion of the margin from the point 71 as a pivot, the slot 33 being described on an arc from said point as a center for preventing lateral shifting of the presser-face 28, the articulating axis 62 of said presser with its operating means rising to the position indicated in Fig. 8, when said fold portion is pressed.

110 Having thus fully described my invention, what I claim as new and desire to secure by Letters Patent, is:

1. In means for pressing flexible material, the combination of an anvil, a pivoted 120 presser having a pressing face coacting with said anvil closely adjacent to said anvil, and an operating part having operative connection with said presser at a greater distance from said presser-face than the distance of 125 said pivot therefrom, said pivoted presser transversely yieldable on its pivot during the pressing operation.

2. In means for pressing flexible material, the combination of an anvil, a pivoted 130

- presser having a pressing face coacting with said anvil closely adjacent to said anvil, and an operating part having operative connection with said presser at a greater distance from said pressing face than the distance of said pivot therefrom, said pivoted presser transversely yieldable on its pivot during the pressing operation, and a spring resisting said yield.
10. 3. In means for pressing flexible material, the combination of an anvil, a pivoted presser having a pressing face coacting with said anvil closely adjacent to said anvil, and an operating part having operative connection with said presser at a greater distance from said pressing face than the distance of said pivot therefrom, said pivoted presser transversely yieldable on its pivot during the pressing operation, a spring resisting said yield, and means for adjusting said spring.
4. In means for pressing flexible material, the combination of an anvil, a pivoted presser having a pressing face coacting with said anvil, operating means having operative connection with said presser, the pivot of said presser operatively located in substantially the plane extended of the material-supporting face of said anvil between said pressing face and said operative connection, and means whereby said pivoted presser is transversely resiliently yieldable on its pivot during the pressing operation.
5. In means for pressing flexible material, the combination of an anvil, a pivoted presser having a pressing face coacting with said anvil, operating means having operative connection with said presser, the pivot of said presser operatively located in substantially the plane extended of the material-supporting face of said anvil between said pressing face and said operative connection, means whereby said pivoted presser is transversely resiliently yieldable on its pivot during the pressing operation, and means for adjusting said presser transversely on its pivot.
6. In a pressing device for flexible material, the combination with a material-support acting as an anvil and having a material-supporting surface, of a presser-body provided with a pressing-face coacting with said surface, actuating means for said presser body having operative connection with said presser body, a pivot for said presser body operatively disposed between said pressing face and said operative connection, said presser-body rockable on said pivot during a portion of its pressing movement and rocked crosswise on said pivot during pressure application of said presser-body, and spring means for resisting said last-named movement.
7. In a pressing device for flexible material, the combination with a material-support having a material-supporting surface,
- of a presser-body provided with a pressing-face coacting with said surface, a pivot for said presser-body, actuating means for said presser-body, said presser-body provided with an arc-slot described on an arc having 70 a point substantially in said pressing-face as a center, said presser-body rockable on said pivot during a portion of its pressing movement and movable along said slot about and transversely on said pivot during the 75 pressure-application of said presser-body, and spring means for resisting said last-named movement.
8. In a pressing device for pressing material, the combination with an anvil having 80 a pressure face, of a presser body provided with a pressing face coacting with the latter, actuating means for said presser body, said presser body provided with a slot extending crosswise of said face, a pivot for 85 said presser body extending into said slot, said presser body rockable on said pivot during a portion of its pressing movement and the walls of said slot movable transversely along said pivot during the pressure 90 application of said presser body, and spring means for resisting said last-named movement.
9. In a pressing device for flexible material, the combination with a material-support 95 having a material-supporting surface, of a pivoted presser-body provided with a presser-face coacting with said surface and having a pivotal axis in substantially the plane extended of said material-supporting 100 surface, said presser-body resiliently yieldable crosswise on said pivotal axis during the pressing operation.
10. In combination, a material-support for flexible material having a material-supporting surface, a pivoted presser-body provided with a presser-face coacting with said material-supporting surface, operating means operatively connected with said body, and a pivot for said body between said last-named connection and said presser-face, the construction and arrangement being such that the material-supporting surface and the pivotal axis are in line when contact is made by said presser-face with the flexible 115 material and the presser-body is moved crosswise on said pivotal axis at said pivotal axis at a point closely adjacent to said presser-face when pressure is applied to said flexible material by said presser-face.
11. In a folding machine for folding the margin of flexible material, the combination of intermittently acting material feeding means, snipping means, folding means, and fold pressing means, comprising a pivoted 120 fold-presser having a fold pressing face, and operating means having operative connection with said fold-presser, the pivot of said fold-presser operatively disposed between said operative connection and said fold 125

- pressing face, said fold-presser yieldable on and at its pivot during its pressing movement transverse to the plane of its pressing face.
- 5 12. In a folding machine for flexible material, the combination of intermittently acting material feeding means, snipping means, folding means, and fold pressing means comprising a pivoted fold-presser having a fold 10 pressing face, operating means for said fold presser having operative connection with said fold-presser, the pivot of said fold-presser being operatively disposed between said operative connection and said fold 15 pressing face, said fold-presser yieldable on and at its pivot during its pressing movement transverse to the plane of its pressing face, and adjustable spring means for resisting said last-named movement.
- 20 13. In combination, a presser having a pressing-face, a pivot member upon which said presser is mounted for oscillatory movement in the pressing operation, and means having provision for permitting said presser 25 to yield on said pivot member and insuring a direction of yield substantially at a right angle to the plane of said pressing-face.
14. In combination, a presser having a pressing-face, a pivot member upon which 30 said presser is mounted for oscillatory movement in the pressing operation, means having provision for permitting said presser to yield on said pivot member and insuring a direction of yield substantially at a right
- angle to the plane of said pressing-face, and means for adjusting the normal relative positions of said presser and said pivot member.
- 35 15. In combination, a presser having a pressing-face, actuating means for said presser, a pivot member between said actuating means and said pressing-face, upon which said presser is mounted for movement in the pressing operation, and means having provision for permitting said presser to yield on said pivot member and insuring a direction of yield substantially at a right angle to the plane of said pressing-face.
- 40 16. In combination, a presser having a pressing-face, actuating means for said presser, a pivot member between said actuating means and said pressing-face, upon which said presser is mounted for movement in the pressing operation, means having provision for permitting said presser to yield on said pivot member and insuring a direction of yield substantially at a right angle to the plane of said pressing-face, and means 45 for adjusting the normal relative positions of said presser and said pivot member.
- 45 50 55 60

In testimony whereof, I have hereunto signed my name, in the presence of two subscribing witnesses.

WILLIAM F. LAUTENSCHLAGER.
